UNITED STATES PATENT OFFICE.

JOHN F. CUNNINGHAM, OF SPRINGFIELD, MISSOURI.

BOILER-FURNACE.

1,216,661.

Specification of Letters Patent.

Patented Feb. 20, 1917.

Application filed July 29, 1915. Serial No. 42,658.

To all whom it may concern:

Be it known that I, JOHN F. CUNNINGHAM, a citizen of the United States, and resident of Springfield, Greene county, Missouri, have invented certain new and useful Improvements in Boiler-Furnaces, of which the following is a specification containing a full, clear, and exact description, reference being had to the accompanying drawings, 10 forming a part hereof.

My invention relates to improvements in boiler furnaces, wherein a plurality of integrally cast units or sections are superposed to form the complete furnace.

15 My invention consists in certain novel features of the construction and arrangement of parts which will be hereinafter more fully described, pointed out in my claim and illustrated by the accompanying drawings, in which:

Figure 1 is a plan, partly in section, of a boiler furnace embodying my improvements;

25 Fig. 2 is a simple longitudinal sectional elevation of the furnace;

Fig. 3 is a transverse sectional elevation taken on the line 3—3 of Fig. 2; and

30 Fig. 4 is a transverse sectional elevation taken on the line 4—4 of Fig. 2.

35 Referring by numerals to the accompanying drawings: 5 designates the base section, which consists of a rectangular casting comprising vertical walls having outstanding base flanges 6 and at their tops an inwardly projecting flange 7. In one of the walls there is formed an opening 8 and on the exterior of the wall adjacent each side of said opening are the perforated ears 9 on which to hinge in a common manner the 40 ash door 10.

11 designates the grate section, which is cast complete as an integral unit of rectangular form of such dimensions as to rest within the base section 5 upon the flanges 7.

45 The casting generally comprises a rectangular water body 12 surrounding the entire section, a water body 13 in communication with the water body 12 and intermediate the end sections of the water body 12 and 50 triangular shaped tubular grate bars between the water body 13 and the forward water body section 12.

Formed in the upper surface of the grate section 11 between the water bodies 13 and the rearmost body 12 is a seat 14, to receive a plate 15, which shuts off the space between

these bodies over the top of the ash pit or interior of the base section 5. 16 designates the fire pot section of the same exterior dimensions as the grate section just described and like said grate section consists of a single unitary casting, comprising a rectangular water body 16^a and the forward portion of this section forms the fire pot 18.

The forward section of this water body is of less height than its remaining portion, to the end that there is formed through the section an opening 19 leading into the fire pot. Projecting forwardly from the front wall of this section and on either side of said opening 19 there are pairs of perforated ears 20, upon which are hinged in a common manner the clinker doors 21, which provide access to the fire pot for tending the fire.

75 The numeral 23 designates units which are of the same general construction as the fire pot section 15 except for the opening 19, their water bodies 24 and 25 forming a magazine 26 for fuel above and registering with the fire pot 18, and the water bodies 27, 80 together with the water bodies 25 and the tubes 28 forming a tubular water boiler.

85 The water tubes 28 are triangular in cross section and are preferably positioned as shown, with one of their points at the top, in order that they require as little cleaning as possible, in that they present side surfaces at angles prohibiting much lodgment of soot and the like.

90 The grate section 12 has projecting laterally therefrom near its top surface the perforated ears 29, and each of the other sections described has similar perforated ears 30, whereby said sections may be secured together in superposed arrangement.

95 The numeral 31 designates the cap section or top of the furnace, which is, like the other sections, cast complete as an integral unit and comprises a single shell fitting over the uppermost one of the sections 23.

100 In the top of this head section 31 there is formed a furnace pipe opening 32, and in one of the side walls thereof there is formed a furnace pipe opening 33, over the one of which I secure the ordinary furnace pipe 34 105 and over the other of which I secure a cap 35, thus providing for extending the furnace pipe from either the side or top of the furnace, as is common.

110 Formed in the top over the magazine 26 is a fuel opening 36, and hinged thereover is a fuel door 37. This section is provided

with the laterally projecting perforated ears 38 whereby it may be secured to the uppermost section 23. The lowermost section 11 is provided with means for connection with a water inlet pipe 39 and the uppermost section 23 is provided with a water outlet connection 40. For establishing communication between the various water bodies of the sections I provide the push-nipples 41, which by preference are fixed in place in certain of the sections, to the end that the sections placed thereover will be automatically placed in communication with the said certain sections by the simple placement over said sections.

It is to be observed from Fig. 2 that the water body 13 of the grate section and the water bodies 25 are spaced apart whereby to provide a passageway 42 for the products of combustion from the magazine and fire pot into the boiler tube section.

By reason of the sectional construction, the furnace may be set up in different heights, that is by using more or less of the units furnaces may be built according to the vertical spaces selected for their occupancy.

Having thus described my invention, what I claim as new therein and desire to secure by Letters Patent of the United States therefore, is:

A boiler furnace comprising in combina-

tion, an integral base unit, having means for access thereto, a grate section having integral water holding bodies forming grate bars, a plate for partially closing communication between the base section and the grate section, a combustion chamber section having an integral water holding body and means for access thereto, a combined fuel magazine and tubular boiler section having integral water holding bodies, forming a fuel magazine over the grate bars at one end of the section, and water tubes at the other end of the section around which the productions of combustion pass, and a top section having a wall dividing the space therein substantially the same as the combined magazine and tubular boiler section, integral means for attaching a furnace pipe thereto and means for gaining access thereto, said sections having the water bodies having means for establishing relative water communication and at least two of the sections having means for connection with service and drain pipes.

In testimony whereof, I have signed my name to this specification, in presence of two subscribing witnesses.

JOHN F. CUNNINGHAM.
